Jonathan Johnson

JONATHAN JOHNSON, OF LOWELL, MASSACHUSETTS.

Letters Patent No. 91,541, dated June 22, 1869.

IMPROVEMENT IN PADS FOR HORSES' HOOFs.

The Schedule referred to in these Letters Patent and making part of the same.

To all whom it may concern :

Be it known that I, JONATHAN JOHNSON, of Lowell, in the county of Middlesex, in the State of Massachusetts, have invented certain new and useful Improvements for Preventing Contraction in Horses Feet, of which the following is a full, clear, and exact description, reference being had to the accompanying drawings, making part of this specification, in which—

Figure 1 is a plan or bottom view of the pad, sheet 1.

Figure 2 is a front elevation, sheet 1.

Figure 3 is a rear elevation, sheet 1.

Figure 4 is a side elevation of my invention applied, sheet 1.

Figure 5 is the absorbent packing applied, sheet 2. A spring, B pad, C strap, sheet 1.

D absorbent packing, sheet 2.

My invention consists in providing an outside adjusting spring, A, extending from the heel to the toe of a horse's foot, with a leather or other strap, C, connected with the spring at the heel and toe, for the purpose of holding the pad B, supporting the absorbent packing D, covering the frog, and filling the space within and above the shoe. The packing being wet, softens the hoof, pressure widens the frog and forces

the heel outward, affording the required space for motion of the vanicular joint and coffin-bone.

The advantages this invention has over other methods of "stopping" (so-called) the foot are: The easy manner in which it is applied and removed, the general use of water, a natural restorative, and its positive action of pressure upon the frog, the spring so formed as to be readily adjusted to the form of the hoof.

In the use of my sandal-pad, persons acquainted with the formation, action, and nature of a horse's foot, will readily understand its application and use.

What I claim, and desire to secure by Letters Patent, is—

1. The spring A, constructed, applied, and arranged in the manner and for the purpose shown and described.

2. The sandal-pad B, constructed, applied, and arranged in the manner and for the purpose described.

3. The combination of the strap C, spring A, pad B, and absorbent D, all constructed, combined, and arranged as and for the purpose described.

JONATHAN JOHNSON.
